Fig. 5

FIG. 1 is a perspective view of the store and recreation shelter building for campgrounds embodying my new design.

FIG. 2 is a side elevational view of said combined building embodying said design.

FIG. 3 is a side elevational view of the side of the building opposite that shown in FIG. 2.

FIG. 4 is an end elevational view of said building.

FIG. 5 is an end elevational view at the end of said building opposite that shown in FIG. 4.

I claim:

The ornamental design for a combined store and recreation shelter building for campgrounds, as shown.
